UNITED STATES PATENT OFFICE.

ANNIE RUDEN AND ELLIS H. RUDEN, OF SEATTLE, WASHINGTON.

MAN'S UNDERGARMENT.

Application filed July 7, 1927. Serial No. 203,930.

Our invention relates to an improvement in undergarments, particularly of the type generally known as men's athletic union suits.

5 One of the objects of our invention is to produce such a union suit in which the front sides, right and left, are made in one piece, the garment as a whole having no buttons, and the neck opening being defined by a 10 yoke or neck piece to hold the garment in shape.

Particularly, it is an object to provide such a garment which has every appearance of an ordinary union suit, which buttons 15 down the front, but which, in fact, has no buttons, at least in the front, and which will be simple and convenient to get into, which will not sag or fall away from the body in any posture, and which has all of the features 20 of the ordinary suit buttoning down the entire front.

25 A further object is the provision in such a buttonless suit of a means for holding the suit in shape at the neck, and of strengthening and preventing the suit from tearing out during the steps of getting into or out of the garment.

It is a further object to form the suit, at 30 least the front pieces thereof, in one continuous piece from shoulder to knee, to make the suit stronger and of better appearance than in the ordinary union suit, wherein they are frequently made in two pieces.

35 A further object is the manufacture of such a buttonless suit involving all of the advantages of a button suit, combined with the advantages of a buttonless suit, and in which a minimum amount of cloth is employed.

40 Our invention comprises the novel parts and the novel arrangement thereof, as shown in the accompanying drawings, described in the specification, and particularly defined by the claims which terminate the same.

45 In the accompanying drawings, we have shown our invention embodied in a man's union suit in the form now preferred by us.

Figure 1 is a front elevation of such a suit laid flat;

50 Figure 2 is a section through such a suit taken through a medial plane on the line 2—2 of Figure 1; and

55 Figure 3 is an inside view of the front of such a garment, taken substantially on the line 3—3 of Figure 2.

Our invention is not concerned with the form assumed by the back side of the garment, or the crotch portion, and hence we shall describe the back portion 1 and crotch portion 10 only as made up in any suitable 60 fashion, including if desired a portion 11 of elastic material to accommodate bending. So far as the present invention is concerned, it is immaterial whether the back portion be made in one or several pieces, and it is likewise immaterial what particular type of crotch and seat portion are employed, and for purposes of simplicity of description the crotch portion will be assumed to form part 65 of the back.

70 The front is formed of two halves which, for convenience, may be designated as the right half 2 and the left half 3. Preferably each of these is formed in one piece, extending from shoulder to knee. These are secured to the back 1 or the crotch portion 10 along the seams 12, 13 and 14. This manner of assembly is customary in such union suits, but ordinarily the inner edges of the front sections 2 and 3 are provided with 75 buttons and buttonholes; in our present garment the construction differs from the ordinary construction, as will be described hereafter. It is desired to point out at this time that while we may describe one section, the 80 right, for example, as having a peculiar construction, and the left as having a different construction, it is largely immaterial whether the right or the left is provided with the construction described, as the pattern 85 might be reversed.

90 With the above understood, it will be noted that the right front piece 2 is provided with a wing 20 extending beyond the medial line which extends vertically of the garment. 95 This wing 20 has its greatest extent at a point between the waist line and the arm pits, at least preferably not lower than the waist and preferably, also, not higher than the arm pits. The edge 21 of this piece 100 swings from the right shoulder inward to the medial line, crosses it, and extends to this point of greatest horizontal extent on the left side of the garment, and between the waist and arm pit levels. The right 105 front piece 3, on the other hand, does not extend past the medial line referred to. Its edge 31 swings inward from the shoulder seam 12 to the medial line, intersecting it at about the same point as the edge 21, and 110

then curves directly downward, following the medial line to the crotch. Thus, with the wing 20 inside of the left front piece 3, the garment has the appearance of the ordinary button garment, and has not the crossed or bodice appearance sometimes associated with buttonless garments. The back, moreover, does not differ in any essential respect from the ordinary athletic type 10 union suit back.

It may be well to note that appearance plays a large part in the purchase of such garments. A man who is accustomed to a given style or cut, will not buy a radically different cut without a compelling reason. If he can be shown that he can eliminate the bother of buttons, in a suit having the appearance of a button garment, without the doubled and redoubled thicknesses, usually 15 associated with buttonless garments, and without the feminine suggestion embodied in a garment wherein the body portions and trunks are from separate pieces, and the waist defined by the seam joining them, he 20 will try the new suit, but first of all the appearance must be approximately that to which he is accustomed. Hence, we lay considerable stress on the fact that the edge of the right front piece 3, which is outermost, follows the usual lines from shoulder to 25 waist, yet the left front piece, underneath, swings over to the right side, to hold it in place on the wearer, and to enable him to get into and out of the garment.

30 The two front pieces 2 and 3 are joined along a horizontal line 32 at about the point of greatest extent of the wing 20, but not thereabove. This permits separation of the two front pieces 2 and 3 above this line 32 for getting in or out of the garment. Below this level the two pieces are seamed together, as indicated at 23, along the medial line, at least to a point 33. Thus there is 35 provided the same effect as two buttons at or near the waist level to hold the two parts of the garment together, yet no buttons are provided, inasmuch as the pieces are stitched together. From the point 33 to the crotch, or a line 34 adjacent thereto, the pieces may 40 be left unsewed to provide a convenience outlet.

45 Across the back, as is best seen in Figures 1 and 2 at the neck, we provide a neck piece 4, preferably of stout woven material, and extensions from this piece continue at either side along the margin of the respective front pieces 2 and 3. Thus the piece 42 extends along the edge 21 of the front piece 2 from the shoulder to the tip of the wing 20, and as this is made preferably of stout 50 woven material with the warp and weft parallel to and at right angles to the edge 21, respectively, it serves as a binder to prevent damage to this edge, and tearing thereof. 55 Similarly, an extension 43 extends along the

edge 31, and this is of like material, but is curved to present the warp of the material parallel to the edge 31 of the garment. This binding strip 43 may extend entirely to the crotch and a second piece 40 may be secured to the right front piece 2 between 33 and 34. This strengthens the outlet at this point, and makes it easy to locate by following the line of the front seam. The lower edge of the wing 20 may or may not be sewed down 60 at 41, just as the maker prefers. It, however, needs no strengthening at this point.

65 In garment construction it is well understood that a yoke or neck piece should be employed, even in the lightest weight garments, and not solely for strength, but as a foundation to keep the garment in position and to mold it to the figure. The neck piece 4, 42 and 43 serves such a purpose in the present garment, but it will be observed that the extension 42 extends across the medial line and to the point of securement along the horizontal line 32 of the wing 20, and the extension 43 does not terminate at this point, but extends on down to the crotch. Thus 70 the garment is firmly held in position, as well as strengthened by this neck piece or yoke and its extensions. This gives life to the garment, it adds to its wear, strengthens it, holds it in position, and makes easy the 75 task of laundering it, especially ironing.

What we claim as our invention is:

1. A man's union undergarment comprising back and right and left front pieces, said front pieces being joined to the back piece along the sides, across the shoulders, and through the crotch, the edge of the left front piece swinging in from the shoulder to a medial line at or about breast level and then downwardly along the medial line to the crotch, the edge of the right front piece swinging in from the opposite shoulder to intersect the edge of the left front piece at or about breast level, and continuing laterally and downwardly beyond the edge of the left front piece, and beneath the left front piece, to a point at or above the waist level, said front pieces being stitched along a horizontal line extending laterally from the medial line, and substantially at this latter level, but not thereabove, and being joined also along the medial line below this level, the edge of the right front piece swinging inward from and below its greatest lateral extension to the medial line above the crotch, the two front pieces being unconnected from the crotch upwards along the medial line for a distance sufficient to leave a convenience outlet.

2. In a man's union undergarment of the type defined in claim 1, a strain-resisting piece secured to the back piece across the neck, an extension of said strain-resisting piece continuing unbroken from shoulder to crotch of the left front piece, and being se- 925

cured to the edge thereof, and another extension of said strain-resisting piece continuing from the shoulder of the right front piece to the horizontal line of stitching.

5. 3. In a man's union undergarment of the type defined in claim 1, and cut from woven material wherein the warp and weft extend substantially transversely and longitudinally of the garment, a woven strain-resisting 10 piece having the warp and weft also extending transversely and longitudinally, said piece being secured to the back piece across the neck, and extending from one side of said neck piece from shoulder to crotch 15 of the left front piece, along the edge thereof, and extending from the other end of said neck piece along the edge of the right front piece to the horizontal line of stitching, said extensions being curved to present 20 the warp of the piece substantially parallel to the edge of the front piece.

4. A man's union undergarment comprising a back piece and right and left front pieces joined along their side edges, at the 25 shoulders and in the crotch to said back piece, both of said front pieces extending diagonally downward in a substantially straight line to the middle of the front, and one only having a wing continuing therebeyond at or above waist level, said front 30 pieces being joined at this level, but not thereabove, by a transverse line of stitching

connecting said wing, from its tip inward to the medial line, with the other front piece, and said front pieces being unconnected 35 along a portion of the medial line, below such transverse line, to leave a convenience opening.

5. A union undergarment comprising connected back and right and left front pieces, the edge of one of said front pieces swinging in from the shoulder to a medial line at or about breast level and then downwardly along the medial line to the crotch, the edge of the other front piece swinging in from 45 the opposite shoulder to intersect the edge of the first-mentioned front piece at or about breast level, and continuing laterally and downwardly beyond the edge of the said first-mentioned front piece, to a point 50 at or above waist level, the upper edge of the back piece, between the shoulders, being a continuous, substantially horizontal curve, said front pieces being stitched along a 55 transverse line from the tip of the lateral extension of the second piece to the medial line, at or above waist level, and the two front pieces being unconnected along a portion of the medial line, below such line of stitching, to leave a convenience outlet. 60
